UNITED STATES PATENT OFFICE.

FRANK E. KINSMAN, OF PLAINFIELD, NEW JERSEY.

ELECTRIC FIRE-ARM.

SPECIFICATION forming part of Letters Patent No. 317,545, dated May 12, 1885.

Application filed November 1, 1883. (No model.)

To all whom it may concern:

Be it known that I, FRANK E. KINSMAN, of Plainfield, in the county of Union and State of New Jersey, have invented certain improvements in Electric Fire-Arms, of which the following is a specification.

Blasting-cartridges and heavy ordnance have been discharged by electricity either by a spark or by the heating of a conductor.

10 My present invention is for the purpose of firing the cartridge in a gun or other portable fire-arm by an electric battery contained within the stock or below the barrel.

15 In carrying out my invention I construct the circuit-connections so that they are brought into action by the trigger, and I lock the parts so that the cartridge cannot be fired until the small of the stock has been grasped preparatory to firing, thereby preventing risk of accidental closing of the circuit.

20 In the drawings, Figure 1 is a side view, partially in section, of a gun with my improvements applied thereto. Fig. 2 is a section in larger size of a cartridge with the circuit-connections. Fig. 3 is a view of the face of the breech-pin, and Fig. 4 shows the parts as adapted to a muzzle-loading gun.

The gun-stock A and barrel B are of ordinary form externally.

30 The gun may be either a muzzle-loader or a breech-loader, as my electric connections or devices are adapted to either.

Within the stock A there is a recess containing a suitable battery, D. It may be a galvanic battery, or a secondary or storage, or any other character of battery. It is to be capable of being closed, so as to prevent the contents being spilled in handling the gun. This is preferably accomplished by leading 35 the conductors b c through insulating-plugs fitted tightly into openings in the battery-case, and by providing a screw-plug, d, at the charging-opening. The battery may be placed beneath the barrel or in any other convenient

40 position. The conductor b passes to the barrel of the gun, or to the breech-piece s, and the conductor c passes to the contact-lever e, that is provided with a bevel end adjacent to but not in contact with the spring circuit-closer h.

50 In consequence of the ends of the spring contact-lever e and circuit-closer h standing at an

incline, there is a rubbing action between the surfaces when the contact-lever e is brought against the circuit-closer h; hence the surfaces are kept clean. I provide a trigger, k, as usual in guns, and I place the contact-lever e in a position to be moved by the trigger, so that when the gun is to be fired the pull of the trigger brings the contact-lever e into contact with the spring circuit-closer h. If these 55 parts only are used, there will be a risk of the electric circuit being closed accidentally and firing the gun. To avoid this I employ the trigger-holder l, in the form of a latch, with a spring-shank attached at 2, and provided with an arm or pusher, m, that projects at one end through the lower part of the gun-stock at the small of the same, so that when the stock is grasped by the hand and the finger extended toward the trigger k the pusher m will be within 65 the hand and pushed in by the grasp of the hand around the small of the stock. This causes the trigger-holder to separate from the trigger, so that the trigger can be operated by hand; but the parts will always be locked out 70 of use, except when the stock is grasped in the right place or purposely unlocked.

When this improvement is used with a muzzle-loading gun, the end of the wire r from the spring circuit-closer h is connected to the wire 80 o, that passes in through a hole in the breech, and is surrounded by insulating material—such as a plug of hard wood or vulcanite—perforated for the passage of the wire, and secured or driven with force into a tapering 85 hole. At the end of this wire o is an exploder in the form of a fine wire of platinum at s', with the other end attached to the barrel or to the breech. In this manner the return-circuit is through the exploder and barrel and the 90 wire b. This exploder may rest upon a piece of glass or other insulated support to protect it from injury.

If two barrels are used, as in a fowling-piece, there will be a trigger to each barrel 95 and one locking mechanism, and the electric circuit is divided into two branches, one leading to the contact-lever of one trigger and the other to the contact-lever of the other trigger. Where metallic cartridge-cases are employed, 100 I make the contact-point by preference at or near the center of the cartridge, as at t. The

conductor is insulated, and the end of the circuit-closer in the breech-pin terminates as a spring, v , which is compressed at t against the rear end of o as the breech is closed. The 5 platina exploder s within the cartridge is connected at one end to the central contact-piece, o , and at the other end to the inside of the case or cap p , holding the insulating material. This is preferably inserted from the front part of 10 either the cartridge or the breech, and rests against a shoulder. Care may be taken to keep the platina wire sufficiently distant from the base of the cartridge to allow for powder in charging the cartridge to pass down around 15 such platina wire. I also remark that usually the conductor in the base of the cartridge may be covered with an insulating material and pass through a zigzag hole in the breech or the base of the cartridge. The return-circuit 20 may be through a second wire instead of the metal of the breech or cartridge. In this case two spring-contacts, v , may be provided in the breech-block s . The circuit-wires may be passed through the hole in the breech-block 25 usually containing the firing-pin. With muzzle-loaders the insulated conductors can be passed through the touch-hole in place of the percussion-cap nipple. In all cases a spark may be used in place of a platina wire where 30 there is an inductorium introduced into the circuit.

I do not claim exploding a cartridge by means of a battery, nor a battery contained in the stock of a gun. By my improvement the 35 circuit is completed through the center of the cartridge, and I am enabled to employ fixed ammunition, and there is no difficulty in closing the circuit, because one contact is made

at the center, and the other contact is through the metal of the gun.

I claim as my invention—

1. The combination, with a cartridge, of an insulated central metallic conductor and a fine wire of platina or similar metal in the powder-space connected at one end to the central metallic conductor and at the other end to the metallic portion of the exterior of the cartridge-case, substantially as specified. 45

2. The combination, in a gun, of an electric battery, a circuit-closer, a trigger to operate 50 the same, and a trigger lock and pusher, substantially as set forth, whereby the trigger-lock is disengaged by the pressure of the hand in grasping the gun.

3. A fire-arm having a chamber adapted to 55 receive a cartridge, a battery or other source of electric energy in the stock or below the barrel, and an insulated conductor at the center of the breech, in combination with a circuit-closer operated by the trigger, and a cartridge having a central insulated conductor in the base, and an incandescent conductor within the powder-chamber, substantially as set forth.

4. The combination, in a breech-loading fire-arm, of a battery, a central insulated conductor in the breech, a conductor connected with the metallic portion of the gun, a trigger, an insulated circuit-closing device actuated by the trigger, substantially as set forth. 65

Signed by me this 29th day of October, A. 70
D. 1883.

FRANK E. KINSMAN.
